US00D927613S

(12) **United States Design Patent** (10) **Patent No.:** **US D927,613 S**
Ryan (45) **Date of Patent:** **** Aug. 10, 2021**

(54) **INCLINER**

(71) Applicant: **InclineRx LLC**, Seattle, WA (US)
(72) Inventor: **David Richard Ryan**, Langley, WA (US)
(73) Assignee: **InclineRx LLC**, Seattle, WA (US)
(**) Term: **15 Years**

(21) Appl. No.: **29/709,860**(22) Filed: **Oct. 17, 2019**

(51) **LOC (13) Cl.** **21-02**
(52) **U.S. Cl.**
USPC **D21/688**

(58) **Field of Classification Search**

USPC D21/688, 686, 689, 690, 760, 769, 707,
D21/694, 797, 802, 811, 814, 818;
D6/349

CLAIM

The ornamental design for an incliner, as shown and described.

DESCRIPTION

FIG. 1 is a top isometric view of an incliner, showing my new design.

FIG. 2 is a bottom isometric view thereof.

FIG. 3 is a front view thereof, which is the same as the rear view.

FIG. 4 is a left side view thereof, which is the same as the right side view.

FIG. 5 is a top view thereof; and,

FIG. 6 is a bottom view thereof.

1 Claim, 4 Drawing Sheets
